UNITED STATES PATENT OFFICE

EDWARD KIRBY BOTTLE, OF ELMIRA, NEW YORK, ASSIGNOR TO AMERICAN SALES
BOOK COMPANY, LIMITED, OF TORONTO, ONTARIO, CANADA, A CORPORATION OF
ONTARIO

MANIFOLDING BOOK

Application filed April 7, 1923. Serial No. 630,579.

This invention relates to an improvement in manifolding books and with respect to its more specific features to three-copy books.

An object of the invention is to provide a manifolding book wherein three copies may be simultaneously made, one of which is opaque and may be retained in the book, the others adapted to be detached and removed.

Another object is to provide a book of the character specified, wherein all of the leaves are opaque, one adapted to be retained in the book, and the others to be detached.

Another object is to provide a book of the character specified, wherein by means of two single faced transfer leaves three copies may be made, all opaque, and one adapted to be retained in the book.

Other objects of the invention will be in part obvious and will in part appear herein-after.

The invention accordingly comprises an article of manufacture possessing the features, properties, and the relation of elements which will be exemplified in the article hereinafter described and the scope of the application of which will be indicated in the claims.

For a fuller understanding of the nature and objects of the invention reference should be had to the following detailed description taken in connection with the accompanying drawing, in which:

Figure 1 is a perspective view of the improved book,

Fig. 2 is a side view of a portion of the book.

This invention is an improvement on a prior invention of Bottle and Yerkes, under Patent No. 1,184,716. In accordance with that invention, two pads of sheets are arranged in position to have the sheets interleaved with each other, the one having a transfer sheet mounted upon the end of the pad. The sheets of the other pad are of tissue. The book is intended to make two opaque and one tissue copy of a record by inserting a tissue superposed upon the carbon between the first and second sheets of the opaque pad.

With such a book, the pad of auxiliary leaves which is intended as the permanent re-

cord is composed of tissue leaves with the record in reverse upon the reverse side, while the two other leaves are both removed from the book.

The patent to Beck #732,257 also shows a salesbook of the same character as that of the Bottle and Yerkes patent above referred to, save only that the sheets of a set are attached together at the end remote from the binding, and the binding of the two books extends in the same direction. This book also makes its record upon the under face of the auxiliary sheet and leaves a tissue record in the book with the writing upon the reverse side.

For many purposes, it is desirable that the permanently bound record shall be of opaque leaves, and preferably of opaque leaves carrying the original record. In accordance with the present invention, a book is produced which is capable of making three copies, all of which may be upon opaque paper, and by reason of the fact that the auxiliary pad is of opaque paper, the permanent record is therefore in durable and easily legible form. Furthermore, the book may be constructed in such a manner that the original record may be made upon the sheet from the auxiliary pad, which is to form the permanently bound record.

The present embodiment of the invention is shown in connection with a cover comprising a body or back 1, and a front or cover portion 2, connected to the body or back by a flexible hinge connection 3. An elongated loop 4 is supported by the back 1 adjacent to the hinge, the loop having one of its side members journaled in a bearing sleeve 5 forming a part of the back. The improved book is composed of two pads, one pad consisting of record leaves 6, which are bound at one end, as indicated at 7 to a support, in the present instance a strip of cardboard 8. The leaves may be bound to the backing 8 in any suitable or desired manner, as for instance by staples, and to the opposite face of the backing from the leaves a tongue 9 of paper board is bound, the tongue being adapted to engage the loop 4, to connect the pad to the holder.

A second pad is connected with the sup-

port or backing 8. This second pad is composed of sets of leaves, each set comprising a leaf 10 and a leaf 11, the said leaves being integral and having between them a weakened line 12, to facilitate the detachment of the leaves from each other. The leaves 10 are bound together, by any suitable binding means, as for instance staples 13, and to a support or backing 14 of cardboard 10 or the like. That end of the support 14 remote from the binding is connected to the end of the support 8 remote from the binding 7, by a hinge connection indicated at 15, and in the present instance a strip of 15 flexible material is used, which is pasted to both backings. With this arrangement the second pad comprising the leaves 10 and 11, may be swung upwardly away from the backing 8, to permit used leaves 6 to be placed beneath the second pad.

Transfer leaves 16 and 17 are provided, the said leaves being bound with the leaves 10 of the sets at the top of the pad, and one of the transfer leaves 17 is adapted to be inserted between the leaves 10 and 11 of the sets, while the other transfer leaf is adapted to be interposed between the top-most set and a leaf 6. Any suitable form or arrangement of lines and printed matter 30 may be provided on the leaves, and in use the leaves 6 are the originals, and are retained in the book as a permanent record. Each of the leaves 10 is provided near the binding with a weakened line 18 for facilitating the separation of the said leaf from the binding.

In using the improved book, when it is desired to make a record, the book is opened, and all of the leaves 6 are turned backward 40 into the position of Fig. 1. By means of a pencil or the like which may be inserted in a notch at the edge of the transfer leaf 16 adjacent to the binding, the transfer leaf may be turned back on the leaves 6, without the necessity for touching the transfer leaf. The leaf 11 of the topmost set is now turned downward, and the transfer leaf 17 is placed on the leaf 10 of the set, after which the leaf 11 is turned back upon the transfer leaf. 45 The transfer leaf 16 is now dropped down, and the adjacent leaf 6 is swung down upon the transfer leaf, as shown in Fig. 1. After the record has been made, the second pad, that is the pad constituted by the leaves 55 10—11 is swung away from the backing 8, and the used leaf 6 is permitted to drop down upon the backing, after which the second pad is turned down upon the used leaf. The book is now ready for another record. 60 Each of the leaves 6 has a weakened line indicated at 19 adjacent to the binding 7, to facilitate the detachment of the leaf if desired.

Since certain changes may be made in the 65 above article and different embodiments of

the invention could be made without departing from the scope thereof, it is intended that all matter contained in the above description or shown in the accompanying drawing shall be interpreted as illustrative 70 and not in a limiting sense.

Having described my invention, what I claim as new and desire to secure by Letters Patent is:

1. A manifolding book including, in combination, a pad of original record leaves, a second pad of sets of record leaves, and common means for supporting said pads with the bound ends extending in the same direction, and with bound end of the first mentioned pad extending beyond the bound end of the other pad, each of said sets of record leaves comprising a leaf bound into said second pad and a second leaf carried by the free end of said bound leaf and having its free end extending backwardly toward the bound end of the pad and two transfer sheets mounted on said second pad, one positioned for insertion between leaves of a set and a second positioned for superposition upon the upper leaf thereof whereby said original record leaves may be superposed upon the second transfer sheet.

2. A manifolding book including, in combination, a pad of sets of record leaves, each of said sets consisting only of a leaf bound at one end thereof into the pad and a second leaf carried by the free end of the first leaf and having its free end extending backwardly toward the bound end of the pad, and two transfer sheets bound into said pad at the same end thereof as the binding of said record leaves, one transfer sheet positioned for insertion between the leaves of a set and the second transfer leaf positioned for superposition upon the upper leaf of a set.

In testimony whereof I affix my signature.

EDWARD KIRBY BOTTLE.
